(57) **CLAIM**

The ornamental design for an aerosol container with actuator overcap and base, as shown and described.

DESCRIPTION

FIG. 1 is an upper perspective view of an aerosol container with actuator overcap and base showing the new design;

FIG. 2 is a right side elevation view thereof;

FIG. 3 is a left side elevation view thereof;

FIG. 4 is a front side elevation view thereof;

FIG. 5 is a rear side elevation view thereof;

FIG. 6 is a top plan view thereof; and,

FIG. 7 is a bottom plan view thereof.
